UNITED STATES PATENT OFFICE.

JOHN T. DANIELS, OF NEWARK, NEW JERSEY, ASSIGNOR TO THE HANSON & VAN WINKLE CO., OF NEWARK, NEW JERSEY, A CORPORATION OF NEW JERSEY.

RHEOSTAT.

1,364,835.

Specification of Letters Patent.

Patented Jan. 4, 1921.

Application filed August 5, 1920. Serial No. 401,287.

To all whom it may concern:

Be it known that I, JOHN T. DANIELS, a citizen of the United States, and residing in Newark, county of Essex, State of New Jersey, have invented certain new and useful Improvements in Rheostats, of which the following is a clear description, the particular novel features being more fully pointed out in the annexed claims.

10 My improvements relate particularly to rheostats for low voltage but heavy current work, such as is required in electroplating or kindred arts, where fine regulation of strong currents by means of rheostats is essential.

15 In the ordinary commercial rheostats, the resistance units are usually arranged so, that they are gradually connected in series by the control lever, but they cannot at will also be thrown in parallel to each other or in multiple series, by which latter connections the resistance between the two main terminals of the rheostat may be varied to a very fine degree. By my improved arrangement and manner of connection of the resistance units, 25 the above purpose may be attained in a very simple and convenient manner.

My invention is illustrated in the accompanying drawings, in which—

Figure 1 is a plan view of the rheostat. 30 showing the protecting casing partly broken away;

Fig. 2 is a transverse vertical section on the line 2—2, in Fig. 1 seen in the direction of the arrows, and

35 Fig. 3 is a wiring diagram showing several combinations of the units in multiple series.

Referring to Figs. 1 and 2, 30 is a base plate of appropriate insulating material near 40 the opposite longitudinal edges of which plate are mounted, in parallel to each other, two terminal rails 31 and 33 provided respectively with the binding posts 32, 34, by which the rheostat is connected into the 45 working circuit. Adjacent to each rail is mounted an equal numbered row of terminal blocks 35, the blocks being insulated from their respective rails and from each other by the base plate. Between these two 50 rows of blocks the resistance elements 36 are connected in zig-zag fashion, as is shown in Figs. 1 and 3, so that each block forms the common terminal for the ends of two adjacent resistance units, the opposite ends of

which are connected to two adjacent blocks 55 of the opposite row.

To each terminal block 35 is conductively fastened one end of a contact leaf spring 37, the opposite ends of the springs extending over the adjacent terminal rail. This is 60 clearly shown in Figs. 1 and 2.

Each spring 37 is slotted midway between its ends and each spring has disposed in its slot a lifting finger 38 of insulating material, this finger being held in place by means of a 60 pivot pin 39 which seats in a semi-circularly curved portion of the spring, so that the inner end of the finger is forced by the spring tension against the terminal rail over which the spring is located. Each spring is shaped 70 so that when its finger is thrown by the operator toward the center of the rheostat, the free spring end is lifted off its respective terminal rail, and when its finger is thrown outwardly the free end is permitted to seat on 75 the rail and to establish an electric contact therewith. These two respective portions of the fingers and springs are clearly shown in Fig. 2.

By this arrangement two banks of switches 80 are created on the rheostat, by which the individual resistance units may be connected between the terminal rails in any desired manner as will now be described with reference to Fig. 3. In this diagram the resistance 85 units are shown for convenience by heavy straight lines, numbered from 1 to 19, and only those switches, which are assumed to be closed, are indicated by a dotted arc.

If now, for instance, the upper end of 90 unit 1 is connected to its terminal rail 31 and the lower end of unit 3 is connected to its rail 33, then units 1, 2, 3 are connected in series between rails 31 and 33.

Likewise if the upper end of unit 6 is connected with rail 31 in addition, units 4, 5 and 6 are connected in series between the two rails and form a group in parallel to the above described unit group 1, 2, 3. Further smaller or larger series groups may be 100 added in multiple, for example, by closing the switches at the upper ends of units 12 and 14 and at the lower ends of units 11, 13 and 15; or also only the switch at the upper end of unit 1 and at the lower end 105 of unit 19 may be closed, when all units are thrown in series. In other words, this arrangement affords the possibility for the op-

erator to quickly and conveniently produce many series and multiple series connections of the units, and thus to vary the resistance of the rheostat within very fine steps, which in the ordinary control lever operated rheostats would require a large number of units and a number of individual rheostats.

The resistance units are protected from mechanical injury by a casing 40 (shown in Figs. 1 and 2) against which the banks of switch fingers may conveniently rest, when the switches are open, and thus the condition of each bank may be observed by the operator at a glance. Ventilation openings 41 may be provided in the top and sides of this casing to permit air cooling of the resistance units.

I claim:—

1. A rheostat of the character described, comprising two terminal rails mounted in parallel to and a distance apart from each other, two rows of terminal blocks mounted between the rails, one row adjacent to each rail, a plurality of resistance units connecting the blocks of said opposite rows in zig-zag fashion, and a bank of switches for each row, adapted to individually connect each block with its adjacent rail at will.

2. A rheostat of the character described, comprising two terminal rails mounted in parallel to and a distance apart from each other, two rows of terminal blocks mounted between the rails, one row adjacent to each rail, a plurality of resistance units connecting the blocks of said opposite rows in zig-zag fashion, and a bank of switches for each row containing one switch for each block.

each switch consisting of a leaf spring fastened at its inner end to its block and having its outer end extending over the adjacent rail, a lifting finger pivotally attached to each spring intermediate the finger ends and resting with its inner end against the rail to permit, when moved on its pivot in one direction, the seating of the free spring end on the rail, and, when moved in the other direction, lifting the said spring end from the rail.

3. A rheostat of the character described, comprising two terminal rails mounted in parallel to and a distance apart from each other, two rows of terminal blocks mounted between the rails, one row adjacent to each rail, a plurality of resistance units connecting the blocks of said opposite rows in zig-zag fashion, and a bank of switches for each row, containing one switch for each block, each switch consisting of a leaf spring fastened at its inner end to its block and having its outer end extending over the adjacent rail, a lifting finger pivotally attached to each spring intermediate the finger ends and resting with its inner end against the rail to permit, when moved on its pivot in one direction, the seating of the free spring end on the rail, and, when moved in the other direction, lifting the said spring end from the rail, and a protecting casing, covering said resistance units, and serving as an abutment for the free ends of all of said switch fingers when their respective contact springs are lifted from the rails.

JOHN T. DANIELS.
